VENTILATING PANEL FOR A COMPUTER CABINET OR THE LIKE

Walter F. Creigh, Newport, Minn.
(Univac Park, St. Paul 16, Minn.)

Filed Sept. 8, 1960, Ser. No. 62,067

Term of patent 14 years

(Cl. D62—4)

FIGURE 1 is a front perspective view of a ventilating panel for a computer cabinet or the like embodying my new design.

FIGURE 2 is a vertical sectional view taken in the direction of the arrows along the lines 2—2 of FIGURE 1.

FIGURE 3 is a top plan view thereof.

FIGURE 4 is a bottom plan view thereof.

The side and end not shown are substantially the same in appearance as the side and end, respectively, shown.

The essential features of my design reside in the portions shown in full lines.

I claim:

The ornamental design for a ventilating panel for a computer cabinet or the like, substantially as shown and described.
